UNITED STATES PATENT OFFICE.

HUGH H. BYRNE, OF LA CROSSE, WISCONSIN.

TOILET-CASE.

No. 818,412.

Specification of Letters Patent.

Patented April 24, 1906.

Application filed September 7, 1905, Serial No. 277,465.

To all whom it may concern:

Be it known that I, HUGH H. BYRNE, a citizen of the United States, residing at La Crosse, in the county of La Crosse and State of Wisconsin, have invented certain new and useful Improvements in Toilet-Cases, of which the following is a specification.

For a full description of the invention and the merits thereof and also to acquire a knowledge of the details of construction of the means for effecting the result reference is to be had to the following description and accompanying drawings, in which—

Figure 1 is a top plan view of a toilet case or box embodying the invention, the same being open. Fig. 2 is a longitudinal sectional view. Fig. 3 is a transverse sectional view, the case closed.

Corresponding and like parts are referred to in the following description and indicated in all the views of the drawings by the same reference characters.

This invention embodies a novel form of toilet case or box for travelers, the same being particularly designed to afford a convenient arrangement of compartments adapted to receive toilet articles or the like, the case being adapted to be readily placed in a satchel, trunk, or suit-case, as found desirable by the user.

In the drawings the numeral 1 designates the body or case proper, the same having a hinged or similarly-connected cover 2. The cover 2 is provided with a flap 3 to overlap a side of the case, and this flap has two or more tabs 4 with fasteners attached to engage suitable means on a side of the box to hold the cover closed. The box is interiorly divided into a number of compartments, a main compartment 5, two transverse smaller compartments 6, and a single transverse compartment 7, having the capacity, preferably, of the two small compartments 6. Transverse partitions 8 and 9 form the transverse compartments 6 and 7, a longitudinal partition 10 separating the compartments 6 and connecting the partitions 8 and 9 at a point between the ends thereof. The main compartment 5 is provided with an annular partition 11, forming an inner auxiliary compartment 12, which is adapted to receive a razor, strop, shaving-stick, nail-file, comb, brush, or the like. The compartment 5 comprises the space between the partition 11 and the sides of the box, and this compartment is adapted to receive collars or similar articles. The

smaller transverse compartments 6 may be utilized to receive a soap-box, tooth-powder, or toilet accessories of a similar nature. The larger transverse compartment 7 is suitable for holding ties, &c. All of the partitions 8 and 11 terminate at the upper edges some distance below the upper edges of the sides of the case, and this admits of the use of the flaps 13 on the under sides of the cover 2, said flaps being adapted to overlap and hold cuffs, ties, stationery, or the like upon the under side of said cover. The flaps 13 are secured over the articles covered thereby by means of suitable straps 14, and when the said flaps 13 hold articles of some bulk it will be seen that the space left above the partitions in the body of the case will be taken up and the flaps will serve to prevent displacement of any articles in the compartments 5, 6, 7, and 12. The partition 9 and one end of the annular partition 11 are brought together in meeting relation, and the meeting portions of the partitions are cut away, as shown at 15, so that the handle of the brush placed in the compartment 12 may extend across the upper portion of the compartments 6. The back of the brush may thus be disposed flush with the upper edge portions of the partitions 9 and 11, and the handle of the brush would under certain conditions serve to hold articles in the compartments 6 from rattling or play, which would be undesirable for obvious reasons. The longitudinal partition 10 terminates at its upper edge flush with the lower edge of the cut-away portion 15, so that said partition 10 will not interfere with the disposition of the brush in a manner before described.

It will of course be understood that a toilet-case constructed as hereinbefore set forth may be suitably finished according to the whim of the manufacturer and the price for which the article may be sold and may be used on the bureau or in any similar way.

Having thus described the invention, what is claimed as new is—

1. In a toilet-case, the combination of a body, a cover therefor, flaps attached to the under sides of the cover, means for securing said flaps so as to inclose articles therein, the body of the case being divided into a plurality of transverse compartments, and a main compartment, and an annular partition arranged in the main compartment and forming a separate compartment for holding toilet articles.

2. In a toilet-case, the combination of a body, a cover therefor, flaps attached to the under sides of the cover, straps for securing said flaps so as to inclose articles therein, a plurality of partitions dividing the body of the case interiorly into transverse compartments, a longitudinal partition separating one of the transverse compartments into two smaller compartments, an annular partition in one of the compartments, and means for securing the cover in closed position.
3. A toilet-case of the type described, comprising a body, a cover therefor, the body of the case being separated interiorly by the transverse partitions 8 and 9 forming the smaller compartments 6, the larger compartment 7, and the main compartment 5, the

main compartment 5 having the annular partition 11 therein disposed with one end of said annular partition against the adjacent transverse partition 9, the central portion of the partition 9 and the adjacent end of the partition 11 being cut away as shown at 15, and the longitudinal partition 10 separating the compartments 6 and having its upper edge flush with the cut-away portion 15 of the partitions aforesaid.

In testimony whereof I affix my signature in presence of two witnesses.

HUGH H. BYRNE. [L. s.]
